UNITED STATES PATENT OFFICE

CORYDON F. BATTERSHELL, OF WICKLIFFE, OHIO

GRAVITY-CONTROL LOCK

Application filed July 18, 1927. Serial No. 206,623.

The object of this invention is to provide a gravity control lock of novel construction for mystery boxes such as are used to contain private or confidential papers, data, or the like.

The gravity control lock embodied in this invention comprises an arrangement of locking bolts and ball obstructions therefor, all being carried by the door of the box and a panel fastened thereto.

This invention is characterized by the simplicity of construction of the locking mechanism. By availing of gravity for the movement of the various parts of the mechanism this simple construction is afforded.

With these and other objects in view, as will in part hereinafter become apparent and in part be stated, the invention comprises certain novel constructions, combinations and arrangements of parts as subsequently specified and claimed.

For a full understanding of the invention reference is to be had to the following description and accompanying drawings, in which:

Figure 1 is a perspective of a mystery box with the improved gravity control lock applied thereto.

Figure 2 is a front view of the panel with the top removed when the bolts are in the locked position.

Figure 3 is a front view of the panel with the top removed with the locking mechanism in a half locked position.

Figure 4 is a front view of the panel with the locking mechanism in the unlocked position.

Figure 5 is a detailed cross section taken from the side on the line 5—5 of Figure 2.

Figure 6 is a detailed cross section taken from the side on the line 6—6 of Figure 3.

Figure 7 is a detailed cross section of the panel taken on the line 7—7 of Figure 3.

Figure 8 is a detailed cross section taken from the side on the line 8—8 of Figure 4.

Figures 9 to 17, inclusive, are showings of the box in the various positions in which it is necessary to place it in order to cause the top to become unlocked.

While one form of the invention is herein-after set forth it is to be understood that it is

not to be limited to the exact construction set forth, because various modifications of these details may be provided in putting the invention into practice within the purview of the appended claims.

55

The box 1 is a mystery box which is bodily movable. This box has the cover or door 2 hinged thereto at one end, as shown at 3, while in the present form this cover is shown hinged to the box it is to be clearly understood that the attachment at this end of the cover may be of any form found suitable. At the other end of the box a hasp 4 is securely fastened to the box. This hasp may be of any suitable construction so long as it has an opening 5 therein to be engaged by a locking bolt in the top. This hasp has the opening 5 which is engaged by the locking bolt to afford the locking of the box.

60

Reference may now be had to Figures 2, 3 and 4, which show the locking mechanism as it is arranged in the top and panel or carrier member. Mounted on the inside of the top 2 in some suitable manner, as by screws, is the panel or carrier member 6. This panel has the opening 7 in one end in which the hasp 4

65

enters. The longitudinal groove or passage 8 has the transverse grooves or passages 9 and 10 communicating therewith at the end opposite the opening. The locking member or

70

bolt 11 is movably fitted in the groove 8 and passes through the opening 5 in the hasp when the device is in locked position. It is notable that when the bolt 11 is in locking position it abuts the end of the groove 8. To

75

prevent the locking bolt from becoming disengaged from the hasp the keeper member or bolt 12 is movably fitted in the groove 9. The keeper member or bolt 13 is also movably fitted in the groove 10. This bolt prevents

80

the box from becoming unlocked if the locking bolt should pass the keeper bolt 12. This is clearly brought out in Figure 3.

85

To hold the keeper bolt 12 in position across the groove 8 so that it will obstruct the movement of the locking bolt ball obstructions 14 are provided. These balls are in the recess 15 in the panel where they are freely movable. This recess 15 communicates with the groove 9 but is deeper than said

100

groove. It also cooperates with the recess 16 in the top to allow for the desired movement of the balls.

At the end of the groove 10 is a recess 17 in which are the ball obstructions 18. The bottom of the recess 17 has a sharp inclined portion at one end thereof, while the other end is inclined very slightly in the opposite direction. These inclined portions of the bottom provide a ridge 19. This recess is sufficiently large to allow the balls 18 to move longitudinally therein. It will be noted that when the ball obstructions are in certain positions in the recesses they prevent the keeper bolts 12 and 13 from being slid back out of the groove 8, but upon movement of these balls to other positions in their recesses these keeper bolts will be movable out of their obstructing position in the groove 8.

For the locking bolt 8 to pass the first keeper bolt to assume a half locked position it is necessary for the ball obstructions 14 to be in the position shown in Figure 6, that is, when one ball is in one end of the recess 15 the other ball is in the recess 16 in the top. In order that the locking bolt may assume the unlocked position shown in Figure 4, it is necessary that it pass the keeper bolt 13. This bolt is moved back between the balls 18 when they are in the position shown in Figure 8, one ball being in each end of the recess.

The operation of the above described locking mechanism depends on gravity, as previously stated. Starting with the box in locked position, in order to unlock it it is necessary to place it in position 1 shown in Figure 9, when in this position one of the balls 14 will enter the recess 16 in the top. The box is then inclined to the position 2 seen in Figure 10, causing the other ball 14 to be moved to the end of the recess 15. When the box is placed on its side, in position 3 shown in Figure 11, the keeper bolt 12 will fall into the recess 15, clearing the groove 8. Upon placing the box in position 4, shown in Figure 12, the locking bolt 8 will slide past keeper bolt 12 and abut the keeper 13. When the bolt 11 is in this position it prevents the keeper 12 from moving into the groove 8. In order to move the keeper 13 from the path of the locking bolt the box is placed in the position 5, shown in Figure 13, and tilted to position 6 shown in Figure 14. When in this position both the balls 18 will be moved to one end of the recess. Upon a slight inclination of the box in the opposite direction it will assume the position 7, shown in Fig. 15, in which position one of the balls 18 will move to the other end of the recess. The box is then turned on its side to position 8, shown in Figure 16, allowing the keeper 13 to fall between the balls 18. Upon placing the box in the position 9, shown in Figure 17, the locking bolt 11 will fall past the keeper 13 to the bottom of groove 8 unlocking the box.

In order to lock the box it is merely necessary to close the top and incline the box forwardly so that the locking bolt 11 will pass through the opening 5 in the hasp. Upon sidewise rocking motion of the box the keeper bolts 12 and 13 will move across the groove 8 holding the locking bolt in position. Only the series of movements set forth in the preceding paragraph will unlock the box and to any one unacquainted with series of movements necessary to successfully unlock the door or cover the interior of the box is inaccessible for obvious reasons.

Using the same idea as embodied in this invention more keeper bolts could be provided, but it has been found that two keeper bolts are sufficient for ordinary use. Of course, if more bolts were used it would require an entirely different series of movements to unlock the box.

To afford variability in the combinations which will open the box the particular arrangement of the passages and recesses connecting therewith may vary, as it is found desirable. By including more passages which house the keeper bolts an almost infinite number of combinations which would open the box are obtainable. These combinations would be provided by merely transposing the keeper members from one passage to another and also by interchanging the recesses in which the ball obstructions move.

Having thus described my invention, what I claim as new and desire to secure by Letters Patent of the United States, is:

1. Gravity control locking mechanism for boxes and the like, comprising a carrier member having passages and recesses therein, a locking member and keeper members therefor movable in said passages, and means in said recesses for obstructing the movement of said keeper members, whereby the members are held in locking position.

2. Gravity control locking mechanism for boxes and the like, comprising a panel having grooves and recesses therein, a locking bolt movable in one of said grooves, keeper bolts also movable in the other of said grooves adapted to obstruct the movement of the locking bolt, and means in the recesses for obstructing the movement of the keeper bolts whereby the bolts are held in the locking position.

3. Gravity control locking mechanism for boxes and the like, comprising a panel having longitudinal and transverse grooves, a locking bolt movable in said longitudinal groove, keeper bolts also movable in said transverse groove obstructing the movement of said locking bolt, and means obstructing the movement of said keeper bolt, whereby the bolts are maintained in locking position.

4. Gravity control locking mechanism for mystery boxes and the like, comprising a panel having longitudinal and transverse

grooves and recesses therein, a locking bolt movable in said longitudinal groove, keeper bolts also movable in said transverse groove obstructing the movement of the locking bolt, and balls in said recesses for obstructing the movement of said keeper bolts whereby the bolts are held in locking position.

5. A mystery box of the class described, comprising a box, a cover for said box, and 10 mechanism for locking the cover to the box, said locking mechanism comprising a hasp secured to the box, a panel having grooves and recesses fastened to the cover, bolts movable in said grooves, one of said bolts being adapted 15 to engage the hasp, and means in said recesses to obstruct the movement of certain of said bolts whereby the bolts are held in locking position.

6. In combination with a box, a lock and 20 gravity control locking mechanism, comprising a hasp, a carrier member having passages and recesses therein, a locking member in one of said passages adapted to engage the hasp, keeper members movable in other of said 25 passages, and means in said recesses for obstructing the movement of said keeper members whereby the locking member is held in engagement with the hasp.

7. In combination with a box, a lock and 30 gravity control locking mechanism comprising a hasp, a panel having grooves one of which is aligned with the hasp, a bolt in said groove adapted to engage the hasp, keeper bolts movable in other of said grooves, and 35 means in said recesses for obstructing the movement of said keeper bolts whereby the locking bolt is held in engagement with the hasp.

8. In combination with a bodily movable 40 box having a cover, a gravity control locking mechanism comprising a hasp, a panel having grooves and recesses therein fastened to the cover of the box, bolts movable in said grooves, one of said bolts engaging the hasp 45 to lock the cover on the box, and balls movable in said recesses to obstruct the movement of certain of said bolts whereby the bolts are kept in locking position, said balls being movable out of the path of the bolts to permit the 50 unlocking of the box.

9. In combination, with a bodily movable box having a cover, of a gravity control locking mechanism comprising a hasp, a panel 55 having an opening adapted to receive the hasp and grooves and recesses on one face thereof, one of said grooves being longitudinal and the others transverse and communicating with the longitudinal groove, said 60 panel being fastened to the cover, a locking bolt in a longitudinal groove, keeper bolts in the transverse groove, and balls in the recesses to obstruct the movement of the keeper bolts whereby the locking bolt is kept in engagement 65 with the hasp, said balls being mov-

able out of their obstructing position to permit the unlocking of the box.

10. In combination with a box, a lock and gravity control locking mechanism comprising an apertured hasp, a panel having grooves one of which is adapted to align with the aperture of the hasp, said groove having a bolt movable therein for engagement in the aperture of the hasp, keeper bolts movable in other of said grooves, said panel having recesses at the ends of the latter grooves and means in said recesses for obstructing the movement of the keeper bolts to obstruct the movement of the locking bolt.

In testimony whereof I affix my signature. 80
